UNITED STATES PATENT OFFICE

94,161

DESIGN FOR A MUSICAL INSTRUMENT

Harry Pullen, Easton, Md., assignor to Fireside
Players, Incorporated, Baltimore, Md., a cor-
poration of Delaware

Application September 22, 1934, Serial No. 53,375

Term of patent 14 years

To all whom it may concern:

Be it known that I, Harry Pullen, a subject of the King of Great Britain, residing at Easton, in the County of Talbot, and State of Maryland, have invented a new, original, and ornamental Design for a Musical Instrument, of which the following is a specification, reference being had to the accompanying drawing, forming part thereof.

Figure 1 is a perspective view of the article, showing my design.

Figure 2 is a bottom view.

The design comprises a rectangular casing of

greatest depth along its longitudinal center line, with a lid conforming to the shape of the side edges of the casing adjacent its front and rear edges but outwardly arched along its central portion to define generally crescent shaped openings at either end.

I claim:

The ornamental design for a musical instrument as shown and described.

In testimony whereof I affix my signature this 21 day of September, 1934.

HARRY PULLEN.
